UNITED STATES PATENT OFFICE.

FREDERICK C. CUTTING, OF ROCHESTER, NEW YORK, ASSIGNOR TO
LAMSON CONSOLIDATED STORE SERVICE COMPANY, OF NEWARK,
NEW JERSEY.

PNEUMATIC-DESPATCH-TUBE APPARATUS.

SPECIFICATION forming part of Letters Patent No. 681,042, dated August 20, 1901.

Application filed December 3, 1900. Serial No. 38,595. (No model.)

To all whom it may concern:

Be it known that I, FREDERICK C. CUTTING, of Rochester, in the county of Monroe and State of New York, have invented certain new and useful Improvements in Pneumatic-Despatch-Tube Apparatus, of which the following is a specification.

My invention relates to improvements in pneumatic-despatch-tube apparatus wherein carriers are despatched through a tube in one direction by vacuum and in the opposite direction by pressure through the same tube.

In carrying out my invention I have provided mechanism for connecting the transmission-tube with either the vacuum side of the blower or the pressure side of the blower, so that carriers may be transmitted through one and the same tube in opposite directions by pressure or vacuum.

My invention relates to certain novel features hereinafter described, and particularly pointed out in the claims.

In the accompanying drawings, which illustrate a construction embodying my invention, Figure 1 is a front elevation of a terminal containing my improvements. Fig. 2 is a side view, partly in section, of the terminal shown in Fig. 1.

Like letters of reference refer to like parts throughout both views.

The tube A at its upper end is in communication with the transmission-tube C through the box B and at its lower end is in communication through the switching-tube

E in the switch-box D with either the suction-tube F, leading to the vacuum side of the blower, when a carrier is being transmitted from the opposite terminal by vacuum, or with the tube G, leading to the pressure

side of the blower, when the carrier is being driven by pressure in its rear from the terminals shown in the drawings to an open terminal at the opposite end of the line. Extending upwardly from the upper end of the

transmission-tube C is a delivery-chute H, the lower end of which, H', leads off to one side of the tube C for the delivery of the carrier onto the table H''. The upper end of the tube C is closed by the cover J, carried by the arm

K and pivoted at K', and extending down

from said arm K is a depending finger L, hereinafter described.

When a carrier is to be sent from the terminal shown in the drawings, it is dropped into the top of the tube C and the cover J closed and is held in the top of the tube C and box B by the suction up through the transmission-tube C, box B, tube A, switching-tube E, and suction-tube F. Then the operator pulls the handle L', fast on the shaft L'', to the left, which swings the lower arm L''' of the handle toward the right, and this movement of the arm L''' operates the rod M, pivotally secured thereto and to the link M', which is pivotally secured to the switching-tube E, and said movement of the arm L''' through the rod M and link M' moves the switching-tube E from the position shown in Fig. 1 over into alignment with the pressure-tube G, and the pressure passing through said tube G from the pressure side of the blower passes up through the tube A, across the box B, and into the transmission-tube C and directs the carrier to the opposite end of the line. At the time the handle L' is moved toward the left it releases the spring-pivoted catch L'', which swings up and engages the depending finger L and holds the cover J closed, so that the pressure which is described as entering the tube C cannot open the cover J, but must pass down through the transmission-tube C. At the same time the handle L' is moved to the left it moves the arm N, fast on the shaft L'', downwardly toward the right, and the spring-latch N' on the lower end thereof engages with the pivoted catch N'', carried on the lower end of the depending support N'', and engages with the lug N''' on said pivoted catch N''. When this is taking place, the pressure passing up through the tube G, switching-tube E, tube A, and box B enters the tube C and from the tube C into the pipe C' and into the diaphragm-chamber C'', and the diaphragm raises the catch C'', so that its forward end C''' engages with the lower end of the catch N''. The parts are held in the position previously described by the back pressure behind the carrier, and as soon as the carrier is at the opposite end of the line this back pressure is relieved and the diaphragm falls and causes 100

the parts to be released from the position to which they have been moved. The spring O on the shaft L² then acts and returns the handle L', arm L³, and arm N to the position shown in Fig. 1. At the same time the lug P on the arm L³ moves down the spring-catch L⁴ and releases the cover. This automatic movement of the parts shifts the tube E into alignment with the suction-tube F, so that the parts are all in the position shown in Fig. 1, and this automatic shifting of the tube E is assisted by the spring O' on the shaft O². A carrier coming from the opposite end of the line by vacuum passes up through the transmission-tube C and strikes the cover, which raises and allows the discharge of the carrier through the delivery-chute H, and the cover then closes by gravity.

The catch C³ is fixed fast on the shaft Q, journaled in two lugs Q', and on the end of said shaft beyond the lugs is a spring R, which assists in holding the depending catch N². When the back pressure ceases and the catch C³ drops, the latch N³ moves toward the left and is released from the catch N² by swinging it toward the right, so that the catch N³ passes freely away from the catch N².

By the construction above described I have provided a pneumatic-despatch-tube system in which carriers are despatched in one direction by vacuum and in the opposite direction by pressure through the same tube.

Having thus ascertained the nature of my invention and set forth a construction embodying the same, what I claim as new, and desire to secure by Letters Patent of the United States, is—

1. In a pneumatic-despatch-tube apparatus, a transmission-tube, a suction-tube normally in communication with said transmission-tube, a valve for closing the open end of the transmission-tube, a compressed-air tube, mechanism for establishing communication between the compressed-air tube and the transmission-tube, a device for locking said valve during the transmission of the carrier, mechanism actuated by pressure in the transmission-tube for holding in position the mechanism which establishes communication between the compressed-air tube and the transmission-tube.

2. In a pneumatic-despatch-tube apparatus, a transmission-tube, a suction-tube normally in communication with said transmission-tube, a valve for closing the open end of the transmission-tube, a compressed-air tube, mechanism for establishing communication between the compressed-air tube and the transmission-tube, a device for locking said valve during the transmission of the carrier, mechanism actuated by pressure in the transmission-tube for holding in position the mechanism which establishes communication between the compressed-air tube and the transmission-tube and adapted to be released upon the discharge of the carrier, and automatic means for breaking the communication

between the compressed-air tube and the transmission-tube and for establishing communication between the suction-tube and the transmission-tube.

3. In a pneumatic-despatch-tube apparatus, a transmission-tube, a suction-tube normally in communication with said transmission-tube, a valve normally closing the open end of said transmission-tube, a compressed-air tube, a switching-tube for establishing communication between the transmission-tube and the compressed-air tube or the suction-tube, mechanism for operating said switching-tube, a device for locking said valve during the transmission of the carrier by compressed air, and mechanism actuated by pressure in the transmission-tube for holding in position the mechanism which establishes communication between the compressed-air tube and the transmission-tube.

4. In a pneumatic-despatch-tube apparatus, a transmission-tube, a suction-tube normally in communication with said transmission-tube, a valve normally closing the open end of said transmission-tube, a compressed-air tube, a switching-tube for establishing communication between the transmission-tube and the compressed-air tube or the suction-tube, mechanism for operating said switching-tube, a device for locking said valve during the transmission of the carrier by compressed air, mechanism actuated by pressure in the transmission-tube for holding in position the mechanism which establishes communication between the compressed-air tube and the transmission-tube, and automatic means for breaking communication between the compressed-air tube and the transmission-tube.

5. In a pneumatic-despatch-tube apparatus, a transmission-tube, a suction-tube normally in communication with said transmission-tube, a valve normally closing the open end of said transmission-tube, a compressed-air tube, a switching-tube for establishing communication between the transmission-tube and the compressed-air tube or the suction-tube, mechanism for operating said switching-tube, a device for locking said valve during the transmission of the carrier by compressed air, mechanism actuated by pressure in the transmission-tube for holding in position the mechanism which establishes communication between the compressed-air tube and the transmission-tube, and means for breaking communication between the compressed-air tube and the transmission-tube and for establishing communication between the suction-tube and the transmission-tube.

6. In a pneumatic-despatch-tube apparatus, a transmission-tube, a suction-tube normally in communication with said transmission-tube, a valve for closing the open end of the transmission-tube, a compressed-air tube,

a device for locking said valve during the transmission of the carrier by compressed air, mechanism for holding in position the mechanism which establishes communication between the compressed-air tube and the transmission-tube while the carrier is in transit, and means for breaking communication between the compressed-air tube and the transmission-tube and for establishing communication between the suction-tube and the transmission-tube.

7. In a pneumatic-despatch-tube apparatus, a transmission-tube, a suction-tube normally in communication with said transmission-tube, a valve for closing the open end of the transmission-tube, a compressed-air tube, a device for locking said valve during the transmission of the carrier by compressed air, mechanism for holding in position the mechanism which establishes communication between the compressed-air tube and the transmission-tube while the carrier is in transit, and automatic means for breaking communication between the compressed-air tube and the transmission-tube and for establishing communication between the suction-tube and the transmission-tube.

8. In a pneumatic-despatch-tube apparatus, a transmission-tube, a suction-tube normally in communication with said transmission-tube, a valve for closing the open end of the transmission-tube, a compressed-air tube, a device for locking said valve during the transmission of the carrier by compressed air, mechanism for holding in position the mechanism which establishes communication be-

tween the compressed-air tube and the transmission-tube while the carrier is in transit, and means for breaking communication between the suction-tube and the transmission-tube and for establishing communication between the compressed-air tube and the transmission-tube.

9. In a pneumatic-despatch-tube apparatus, a transmission-tube, a suction-tube normally in communication with said transmission-tube, a valve for closing the open end of the transmission-tube, a compressed-air tube, a device for locking said valve during the transmission of the carrier by compressed air, mechanism for holding in position the mechanism which establishes communication between the compressed-air tube and the transmission-tube while the carrier is in transit, automatic means for breaking communication between the compressed-air tube and the transmission-tube and for establishing communication between the suction-tube and the transmission-tube, and manually-operated means for breaking communication between the suction-tube and the transmission-tube and for establishing communication between the compressed-air tube and the transmission-tube.

In testimony whereof I have signed my name to this specification, in the presence of two subscribing witnesses, this 21st day of November, A. D. 1900.

FREDK. C. CUTTING.
